SERVING BOTTLE

Max A. Weisbrot, Chicago, Ill.

Application December 1, 1951, Serial No. 17,581

Term of patent 14 years

(Cl. D58—8)

To all whom it may concern:

Be it known that I, Max A. Weisbrot, a citizen of the United States, residing at Chicago, in the county of Cook and State of Illinois, have invented a new, original, and ornamental Design for a Serving Bottle, of which the following is a specification, reference being had to the accompanying drawing, forming part thereof.

Fig. 1 is a front elevational view of a serving bottle showing my new design;

Fig. 2 is a side elevational view; and

Fig. 3 is a top plan view thereof.

I claim:

The ornamental design for a serving bottle, substantially as shown.

MAX A. WEISBROT.
